CLAIM

The ornamental design for a ladder, as shown and described.

DESCRIPTION

FIG. 1 is a perspective view of a ladder.

FIG. 2 is a front side view of the ladder of FIG. 1.

FIG. 3 is a rear side view of the ladder of FIG. 1.

FIG. 4 is a right side view of the ladder of FIG. 1.

FIG. 5 is a left side view of the ladder of FIG. 1.

FIG. 6 is a top side view of the ladder of FIG. 1; and,

FIG. 7 is a bottom side view of the ladder of FIG. 1.

The broken lines in the figures are shown for the purpose of illustrating boundaries of the ladder and form no part of the claimed design.

1 Claim, 7 Drawing Sheets
